UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed April 23, 1924. Serial No. 708,355.

My invention relates particularly to what is commonly termed a "motor starting switch." My former Patent, No. 1,477,871, of Dec. 18, 1923, shows a switch of the same general type. My former patent, however, shows a construction particularly adapted in detail to a 3-wire system, whereas my present invention is particularly directed to a switch for use with a four-wire system. 10 The main object is to provide a simple but rugged and reliable construction of this type which may be opened and closed by hand, but which is adapted to open the circuit automatically upon undue variations in the 15 load in any leg of the circuit.

Because of the fact that there is no difference in voltage between the phases of 2-phase circuits, the under-voltage release coil will not operate if connected between the 20 over-load relays of the two phases. It becomes necessary, therefore, to employ 2 coils, one in each phase. The special object of my invention is to design an apparatus of this character so that the same type coil construction 25 may be used with each phase.

I accordingly employ two separate electromagnets, one connected across each phase through the over-load relay. The main switch is controllable by manually-operable 30 means for opening and closing the circuit and a spring for automatically opening the circuit. One of the magnets normally holds the switch in a closed position and the other magnet controls a supplementary switch 35 which is in circuit with the coil of the first magnet. The over-load relays are preferably of the closed contact type, such, for instance, as more fully set forth in my Patent 1,569,364, dated January 12, 1926. I have 40 constructed the parts so that the supplementary switch can be adjusted for voltage trip in a simple manner.

Fig. 1 is a perspective view of a construction embodying the improvements of my invention, the switch being shown in the normal closed circuit operating position.

Fig. 2 is a diagrammatic plan view showing the circuits.

Fig. 3 is a side view of one of the control magnets and the supplementary switch controlled thereby.

Fig. 4 is an edge view and section of the contacts of the supplemental switch of Fig. 3.

The switch is provided with upper cir-

cuit terminals 5, 6 and 7, 8 for the respective phases, and with lower terminals 9, 10 and 11, 12. Movable switch members, for instance of knife blade type 13, 14, 15, 16 are provided for opening and closing the lines. These blades are preferably hinged at the lower ends, as at 17, 18 and 19, 20. The upper ends of the blades are connected by an insulating crossbar 21, which is provided with hook or loop-like members 22 having a lost motion connection with the operating crank 23, which is adapted to be operated by hand in the usual manner. The cross-bar 21 is also connected to the crank 23 by springs 24 for accentuating the opening movement of the switch. The crank 23 is also connected to a stationary element for instance a wall of the box by a spring 25, which tends to move the crank 23 and the switch blades to an open circuit position.

Over-load relay devices such as 26, 27 are provided for the two phases. The relay 26 has a heating coil 28 connecting the stationary terminals 17 and 9. The intermediate relay clip member 29 is normally electrically connected to the terminal 9 through the bimetallic thermostatic arm 30 and the contact screw 31.

The magnet coil 32 is connected across the first phase between the terminals 29 and 18 and provided with an armature 33 which is pivoted at 34. This armature is connected to the operating crank 23 by means of the bar 35 which has a sliding engagement at its lower end with the pin 36 carried by the armature. The bar is provided with a slot 37 to permit it to move with respect to the pin 36. Roller 38 carried by the armature normally serves as an abutment for the lower end of the bar 35. When the magnet 32 is energized the parts are held in the position shown in Figure 1 as more fully described in my former Patent No. 1,477,871.

The relay 27 may be constructed exactly like relay 26 with a heating coil between terminals 20 and 12 and a thermostatic element connected to intermediate terminals 12 and 39. This terminal 39 is connected to terminal 19 and left hand phase through the magnet coil 40. This latter coil 40 has an armature 41 pivoted at 42 to the supports 43. The plates 44 connected to opposite sides of the armature 41 embrace an arm 45

which carries at its movable end a switch contact 46 which normally connects the spring jaws 47 in the circuit of magnet 32. The spring 48 is provided which normally tends to retract the armature 41 from controlling magnet 40. The tension of this spring may be adjusted by a nut 49 which is adjustable back and forth on the threaded member 50 so as to give the desired impulse 10 to the armature 41 and the switch member 46.

Normally when the switch is closed for operation, the parts are in the position shown in Fig. 1. At this time the current in the right hand phase passes through switch 15 blade 13 and heating resistance coil 28. The other side of this phase passes through blade 14 to terminal 10. The magnet coil 32 and the thermostatic switch member 30 are normally in circuit across this phase, the 20 switch 46, 47 being held closed by the energized magnet coil 40. At this time the magnet coil 32 holds the armature 34 and the rod 35, crank 23 and all the switch blades in a closed circuit position. If the conditions in the left hand phase are normal, the 25 circuit through the relay 27 is closed and the magnet coil 40 is holding the supplementary switch 46, 47 closed. Should the voltage decrease in the right hand phase, the 30 magnet coil 32 will release the armature 33, and the spring 25 will throw the crank 23 and open the circuits through both phases. Should the voltage in the left hand phase fall below a predetermined amount the magnet 35 coil 40 will release its armature 41 and the spring 48 will throw the arm 45 outward and open the circuit between contacts 46 and 47, thus de-energizing the magnet coil 32 and acting to throw the main switch 40 in the same way that a decrease in the voltage of the right hand phase would do.

Should the load of the right hand phase increase above a predetermined amount the heat from the coil 28 would warp the thermostatic switch element 30 in the relay 26 away from the contact 31 and open the circuit of the magnet 32, thus releasing its armature and opening the switch as before. Should the load in the left hand phase be 50 increased above a predetermined amount, the thermostatic element of the relay 27 would open the circuit through the coil 40 and release supplementary switch 46, 47 and open the circuit as above described.

According to my invention, the two magnets 32 and 40 are alike except that one has 55 a slide and hinged connection with the operating crank 23, while the other operates the supplementary switch which is in circuit with the first.

I claim:

1. An enclosed switch comprising four movable switch members, a hand operable crank therefor, a spring tending to move said switch to open circuit position, an electro-magnet in shunt with two of said switch members for holding all of said members in a closed circuit position, a supplemental switch in circuit with said magnet, a second electro magnet connected in shunt 70 with the other two switch members for controlling said supplemental switch, an overload relay in series with each of two of said switch members, each relay having a heating element and a thermostatic member adapted to automatically open the circuits through one of said electro magnets.

2. In an electric switch, the combination of two pairs of switch blades with appurtenant circuit terminals, quick-break mechanism connected to all of said blades for simultaneously operating them to open the circuits, an electro-magnet in shunt relationship to the blades of one pair of said blades for holding the quick-break mechanism in closed circuit position under normal conditions, an auxiliary switch in series with the first mentioned magnet and controlled by the second magnet, and a thermostatic switch member in series with one of the blades of each pair of blades, and a base serving as a mounting for all of said parts.

3. An electric switch construction including a main switch having four movable blades and appurtenant contacts, manual means for operating said switch, a main magnet in shunt relation with two of said blades for holding said switch in closed 100 position while the voltage is substantially normal, an auxiliary switch having contacts in circuit with said main magnet, an auxiliary magnet in shunt relation with the other two blades for holding said auxiliary switch in closed circuit position while the voltage is substantially normal, spring means for throwing said main switch to open circuit position and spring means for opening the auxiliary switch, said main magnet being adapted to release said main switch upon a predetermined decrease in voltage and said auxiliary magnet being adapted to release the said auxiliary switch and open the circuit through the said main magnet and release the main switch upon a predetermined decrease in voltage in the circuit.

BENJAMIN E. GETCHELL.
